UNITED STATES PATENT OFFICE.

HERBERT G. OLIVER, OF MAMARONECK, NEW YORK.

SOFFIT CLIP FOR REINFORCED-CONCRETE STRUCTURES.

Application filed July 1, 1925. Serial No. 40,946.

The present invention relates to improvements in wire soffit clips for reinforcing concrete structures, and more particularly the invention relates to an improvement in the structure disclosed in the patent granted to me June 3, 1924, and numbered 1,496,321, and it has for its principal objects to avoid waste of the soffit clip structure when severing the same from standard lengths; to facilitate the manufacture of the soffit clip; and to provide means for maintaining the soffit clip in condensed form for transportation and storage and to facilitate the preparation of the soffit clip for application to service.

Drawings.

Figure 1 is a broad side view showing the preferred form of a soffit clip constructed and arranged in accordance with the present invention, the clip being shown in its contracted form arranged for transportation or storage.

Figure 2 is a view on enlarged scale showing the under soffit of a fragment of a structural metal beam having applied thereto a soffit clip constructed in accordance with the present invention, and in broken lines is shown, a severed fragment of said clip.

Figure 3 is a cross section of the structure shown in Fig. 2, the section being taken on the line 3—3 in Fig. 2.

Figure 4 is a broad side view of a fragment of the soffit clip showing a modified form thereof.

Figure 5 is a similar view showing a further modification of the structure.

Figure 6 is a similar view showing a further modification of the structure.

Figure 7 is a detailed view on enlarged scale of a clip, the section being taken as on the line 7—7 in Fig. 1.

Description.

As in the structure referred to as disclosed in the prior patent above mentioned, the present clip employs a plurality of runner wires 10. In the preferred form shown in Figure 1 of the drawings, these wires are disposed in spaced relation and are connected at intervals in their length with bridging members 11. In the present invention the bridging members 11 are disposed in pairs and in relatively close relation, the intention being to provide sufficient space between, to conveniently cut the runner

wires between the bridging members, the purpose of which is to permit short lengths of the soffit clip to be severed from the standard lengths without waste of the soffit clip construction, and without allowing the free ends of the runner wires to hang unsupported, or require the alternative thereof, that the mechanic twist the same together. When this is done, it will be appreciated that a considerable loss of time ensues due to the fact that the work is handled by the mechanic when perched on the iron beam and while working thereunder, or in other words, when inconveniently disposed for the purpose mentioned.

Intermediate the bridging members 11 and preferably disposed midway therebetween are clips 12. Each clip 12 as can be best seen in Fig. 7 of the drawings is constructed from a short length of wire, the ends of which are curled around to form loops 13, and an upright extension 14.

The clips when constructed in accordance with the present invention are mashed or compressed to form the breaking sections 15, preferably at the middle or center of the clip length. The breaking sections 15 thus come between the runner wires 10 which are permanently secured to the clip 12 by being spot-welded thereto.

The soffit clips for reinforcing are constructed in long lengths of standard measurement and are delivered in suitable packages to the building under construction. When the soffit clips are installed in service, the mechanic "riding" the beam, starts his work by breaking the clips 12 by bending sharply in successive reversed directions on the sections 15. He then holds the soffit clip below the beam and overturns the extension 14 of the clips 12 to rest over the flange of the beam as shown in Fig. 3 of the drawings.

As shown in Fig. 2 of the drawings, the fragments of the clip 12 when thus disposed are parted with the effect that the intermediate portions of the runner wires 10 operate resiliently to hold the extensions 14 in engaged relation to the flange of the metal beam while the loops 13 serve to hold the runner wires 10 and the parts connected therewith in spaced relation to the said flange or soffit of the beams. When now, as sometimes happens, the standard lengths of the soffit clips are too long or require a small section to fill out the length, the me-

chanic severs the runner wires 10 between the bridging members 11. It will be seen that when this severance is completed, the remnant is preserved intact and in position to be applied to the work or to be disposed on the soffit of the beam.

In Figures 4, 5 and 6 of the drawings certain modifications of the structure, and particularly of the part thereof employing 10 the bridging members 11 are shown.

In Figure 4, short U-shaped members 16 are spot-welded on the runner wires in lieu of the short straight lengths constituting the members 11.

15 In Figure 5, the runner wires 10 are disposed in juxtaposed parallel relation. While so disposed, the clips 12 are spot-welded together and intermediate the clips 12. The welding is performed as at the positions indicated by the numerals 17 and 18. The spots indicated by the numerals 17 and 18 are spaced apart so that when it becomes necessary to sever the soffit clip, the cut can be made between the said spots. But it 20 will be understood in this connection that two spots thus indicated are used for practical manufacturing purposes. It would be possible to elongate the welding or to cover the space between the spots indicated by the 25 numerals 17 and 18 so that in severing the soffit clips, the cut may be made in the center of the welded section. For obvious reasons, however, this is not desired, but it is intended that the claims herewith submitted 30 shall cover such a construction as the equivalent of the two spots indicated by the numerals 17 and 18.

In Figure 6, the runner wires 10 are disposed in the same manner as shown in Fig. 40 5 and at certain points they are twisted together to form the wrapped sections 19. When so constructed, the mechanic can cut through the center of the wrapped section 19 and thereby obtain the frictional portions 45 of the soffit clips desired.

It will be understood that while I have shown and described a preferred and certain modified forms of the invention and of the

means for forming severing sections for the soffit clips, there may be other forms, well-known, which might be employed to serve practically the same purpose and these I wish to be understood as considering within the purview of this invention. 50

I claim:

55 *Claims:*

1. A soffit clip for reinforcing concrete construction comprising a plurality of runner wires disposed in spaced parallel relation; a plurality of clip members structurally secured thereto in perpendicular relation thereto and at suitable intervals; and means for uniting said runner wires between said clip members, said means providing severance areas for retaining said runner wires at opposite sides of the point of severance, said means embodying a plurality of transversely extended members for connecting said runner wires in short spaced relation. 60

2. A soffit clip for reinforcing concrete construction comprising a plurality of runner wires disposed in spaced parallel relation; a plurality of clip members structurally secured thereto in perpendicular relation 65 and at suitable intervals; and means for uniting said runner wires between said clip members, said means providing severance areas for retaining said runner wires at opposite sides of the point of severance, said means embodying a plurality of connections uniting said runner wires in short spaced relation intermediate said clips. 70

3. A soffit clip for reinforcing concrete construction comprising a plurality of runner wires disposed in parallel relation; and a plurality of clip members structurally secured to each of said wires and having terminal extensions for engaging the flange of a structural beam, said clips being provided with a weakened partable section intermediate said runner wires, said partable section embodying a flattened area disposed between 80 said runner wires. 90

HERBERT G. OLIVER.
